(57) **CLAIM**

An ornamental design for a mass airflow housing, as shown and described.

DESCRIPTION

FIG. 1 is a left side isometric view of the mass airflow housing.

FIG. 2 is a front view of the mass airflow housing.

FIG. 3 is a back view of the mass airflow housing.

FIG. 4 is a left side view of the mass airflow housing.

FIG. 5 is a right side view of the mass airflow housing.

FIG. 6 is a top view of the mass airflow housing.

FIG. 7 is a bottom view of the mass airflow housing; and, FIG. 8 is a right side isometric view of the mass airflow housing.

The broken lines depict portions of the mass airflow housing and form no part of the claimed design.
